DISHWASHING MACHINE

George E. Kingsley and Harry J. Loar, Newark, N. J., assignors, by direct and mesne assignments, of two-thirds to said Kingsley and one-third to Eric D. Bovet, New York, N. Y.

Application December 8, 1934, Serial No. 756,618

2 Claims. (Cl. 259—95)

This invention relates, generally, to dishwashing machines, and the invention has reference, more particularly, to a novel construction of dishwashing machine.

5 Dishwashing machines as heretofore constructed are generally more or less complicated in structure and require an undue amount of attention in use, in maintenance and in retaining the same in a clean and sanitary condition. Also, 10 many of these machines fail to thoroughly clean the dishes or require an excessive amount of time and hot water to do so.

The principal object of the present invention is to provide a novel, simply constructed, dishwashing machine that is easy to use, is reliable and efficient in operation and which is easily retained in a sanitary and clean condition.

Another object of the present invention lies in the provision of a novel dishwashing machine of 20 the above character that employs a single impeller for both washing and drying the dishes, as well as for discharging used water from the machine.

Still another object of the present invention is 25 to provide a novel dishwashing machine of the above character wherein the cleansing water is given a swirling motion, and the dishes to be cleaned are so disposed that the motion of the water is substantially tangential to the surfaces 30 of the dishes, thereby effecting a rapid cleansing action.

Other objects of this invention, not at this time 35 more particularly enumerated, will be clearly understood from the following detailed description of the same.

The invention is clearly illustrated in the accompanying drawings, in which:

Fig. 1 is a part vertical sectional view of the 40 novel dishwashing machine of this invention.

Fig. 2 is a part sectional view taken substantially along line 2—2 of Figs. 1 and 4 looking in the direction of the arrows.

Fig. 3 is a sectional view of the container part 45 of the machine taken along line 3—3 of Fig. 2, looking in the direction of the arrows, and

Fig. 4 is an enlarged fragmentary sectional view taken along line 4—4 of Fig. 2, looking in the direction of the arrows.

Similar characters of reference are employed in 50 said views, to indicate corresponding parts.

Referring now to the said drawings, the reference numeral 1 designates the novel dishwashing machine of this invention as a whole, the said machine consisting essentially of a container 2 and 55 a supporting stand or base 3 therefor. Stand 3

has depending legs 4 preferably provided with casters 5 to enable the ready moving of the dish-washer about. The stand or base 3 is of substantially elliptical shape in plan and has a projecting shelf 6 at one end thereof for supporting a driving motor 7 which is illustrated as an electric motor. Motor 7 is preferably enclosed by a casting 8 that may be attached as by rivets to the container 2.

The container 2 is of substantially cylindrical 5 shape and its lower half is formed, adjacent motor 7, with a projecting portion 10 that is of substantially crescent shape as viewed in plan, thereby causing the lower part of the container 2 to be of approximately elliptical shape in plan. A vertical partition 11 is positioned inwardly from the outer end wall of projecting portion 10 and this partition 11 merges at its top into the side wall of container 2. A space or passage 12 is thus provided between partition 11 and the outer wall of 20 projecting portion 10, within which space or passage an impeller 13 is positioned. The hub of impeller 13 is fixed on a shaft 14 that extends through a stuffing box 15 and is connected as by a coupling 16 to the shaft 17 of motor 7.

The blades 18 of impeller 13 are illustrated as 25 of involute shape for efficient operation and the upper half of the impeller 13 is illustrated as covered by an arcuate transverse partition 20 extending between the outer wall of projecting portion 10 and partition 11. Additional transverse partitions 21 and 22 extend between the ends of arcuate partition 20 and the top 23 of projecting portion 10 for aiding, respectively, in conducting 30 water to and from the lower half of impeller 13. 35

A waste water outlet 24 is provided at the discharge side of impeller 13, which outlet is connected through a valve 25 to a hose 26. A slide gate 27 is slidably mounted in guides 28 provided in the projecting portion 10 and has an operating handle 29 positioned exteriorly of this projecting portion. By pulling upwardly upon the handle 29, the gate 27 is raised to its full line position shown in Fig. 4, thereby permitting the impeller 13 in use to discharge water at high 45 velocity from the discharge end 30 of passage 12 and into the interior of container 2 producing a swirling motion of the water therein. By pushing downwardly upon the handle 29, the slide gate 27 will be moved to the dotted line position 50 shown in Fig. 4, in which position the discharge outlet 30 of passage 12 is shut off so that the water from the container 2 is forced up through outlet 24 and through hose 26, provided valve 25 is open. A removable screen 31 is preferably 55

positioned in advance of the inlet opening 32 of passage 12 for straining the water before it reaches the impeller 13.

Container 2 is open at its top and is arranged 5 to be covered by a removable lid 33 having a lifting handle 34. The bottom 35 of container 2 is preferably raised somewhat at its center to aid the circulatory flow of water in cleansing the dishes and to cause water to drain towards 10 the impeller 13. An annular wire frame 37 is adapted to be received within container 2 for resting upon the bottom 35. Frame 37 is constructed to provide a plurality of annular receiving recesses 38, 39 and 40 for receiving and 15 supporting plates, saucers and the like so that they stand on edge and are arranged edge to edge in a ring formation within the container 2 and near the side walls thereof. The frame 37 is shown as having cross wires 41 for dividing 20 the annular receiving recesses 38 to 40 into individual compartments. A central tray 42 is illustrated as having hooked end portions 43 for engaging and resting upon the wire frame 37. The tray 42 is provided with a screen 44 for supporting 25 knives, forks, spoons and the like. Additional open grid trays 45 and 46 have their ends removably mounted on the frame 37 and are adapted to support cups and similar articles. If desired, trays 42, 45 and 46 may be made as a 30 unitary structure, thereby facilitating the insertion and removal of the same with respect to container 2. Additional articles may be placed under trays 42, 45 and 46, if desired.

In use, the dishes to be washed are inserted 35 into the container 2, the respective types of dishes being arranged as just described. Hot or tepid water is then run into the container 2 and some soap or the like should be added. This water may be supplied either through the open top of 40 container 2 or through the hose 26. Preferably, the water level within container 2 will stand as high as the top of wire frame 37 although a much less quantity of water may be used, if desired, especially when but a few dishes are 45 being washed. The cover 33 is then placed on container 2, the slide gate 27 raised and the motor 7 started, thereby causing impeller 13 to rotate in a counter-clockwise direction as viewed in Fig. 4.

50 The rapidly rotating impeller 13 serves to draw water from container 2, through screen 31 and inlet opening 32 and past the lower half of this impeller within passage 12. In passing the impeller 13, the blades 18 thereof impress a high 55 velocity head upon the water, thereby causing this water to flow out through discharge outlet 30 at high speed and back into the container 2. It will be noted that the water reenters the container 2 adjacent its side wall and flows at high 60 speed in a direction substantially parallel to such side wall, i. e. in an annular direction, thereby setting up a swirling motion of the water within the container 2, resulting in the rapid cleansing of the dishes. The direction of flow of 65 the water is parallel to the surfaces of the plates and saucers held by wire frame 37 so that dirt and foreign matter are quickly removed from these surfaces. The swirling water enters the 70 downwardly open cups on trays 45 and 46, thereby rapidly cleaning these cups, while water flows in all directions over the knives and forks on screen 44, thus cleaning the same.

75 After the dishes are thus cleaned, the hose 26 is connected with a drain, the valve 25 opened

and the slide gate 27 lowered. Continued motion of impeller 13 now causes the water to be driven up through outlet 24, valve 25 and hose 26 into the drain, thereby quickly emptying the container 2. After the container 2 is empty, should it be desired to rinse the dishes, the gate 27 is again raised and fresh water inserted into the container and circulated for a time therein by the impeller 13. After rinsing the dishes, the water is again removed by lowering gate 27 and there- 10 after the cover 33 is lifted off of container 2 permitting air to freely enter this container. The gate 27 is now raised and the impeller 23 serves to rapidly circulate drying air over the dishes so that they are quickly dried, after which they may 15 be removed from the washer.

It will be noted that when the wire frame 37 is taken out of the container 2, the interior thereof is unobstructed, thereby enabling easy cleaning of the same. Owing to the simple and 20 rugged construction of the dishwasher, and to the fact that but a single, directly connected, impeller is used, the same requires but little attention in operation and may be used for a long period without any attention whatever. It is to 25 be understood that the container 2 instead of being mounted on the stand 3 may be set into a specially prepared sink, if desired, or this container may be mounted on any suitable supporting surface.

30 As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense.

We claim:

1. In a dishwashing machine, a vertical cylindrical container having a projecting portion at one side thereof, said projecting portion providing an arcuate passage communicating at its ends with said container, a rotatable impeller within 45 said passage, means for rotating said impeller to cause a swirling circulation of water through said container and said passage, a waste water outlet provided in said container adjacent said impeller at the discharge side thereof, and a slide 50 gate for shutting off said passage at the discharge side of said impeller, whereby water may be discharged from said container out through said waste water outlet.

2. In a dishwashing machine, a vertical cylindrical container having a projecting portion at one side thereof, said projecting portion providing an arcuate passage communicating at its ends with said container, a rotatable impeller within 55 said passage, means for rotating said impeller to cause a swirling circulation of water through said container and said passage, a screen provided at the inlet of said passage, a waste water outlet provided in said container adjacent said impeller at the discharge side thereof, and a slide 60 gate for shutting off said passage at the discharge side of said impeller, whereby water may be discharged from said container out through said waste water outlet, the opening of said slide 65 gate after the emptying of said container, enabling said impeller to circulate drying air throughout said container.

GEORGE E. KINGSLEY.
HARRY J. LOAR.
